[57] **CLAIM**

The ornamental design for a garment having printed instructions for self-examination of the breasts, as shown and described.

DESCRIPTION

FIG. 1 is a front elevational view of a first embodiment of a garment having printed instructions for self-examination of the breasts showing our new design;

FIG. 2 is a rear elevational view thereof;

FIG. 3 is a front perspective view thereof;

FIG. 4 is a rear perspective view thereof;

FIG. 5 is a front elevational view of an alternate embodiment of the design shown in FIG. 1, the rear view being identical to FIG. 2;

FIG. 6 is a front perspective view of FIG. 5;

FIG. 7 is a front elevational view of a third embodiment of the design shown in FIG. 1, the rear view being identical to FIG. 2; and,

FIG. 8 is a front perspective view of FIG. 7.

The broken lines shown throughout the views are understood to represent conventional stitching.
